UNITED STATES PATENT OFFICE.

HARVEY E. SHUMWAY, OF FRANKFORT, KANSAS.

DESIGN FOR A CANDLESTICK.

44,943.

Specification for Design.

Patented Nov. 25, 1913.

Application filed July 10, 1913. Serial No. 778,317. Term of patent $3\frac{1}{2}$ years.

To all whom it may concern:

Be it known that I, HARVEY E. SHUMWAY, a citizen of the United States, residing at Frankfort, in the county of Marshall and State of Kansas, have invented a new, original, and ornamental Design for Candlesticks, of which the following is a specification, reference being had to the accompanying drawing, forming part thereof.

The figure is a perspective view of the design.

The candles or lights are supported upon the end portions and angle portion of a horizontally arranged part formed to repre-

sent a conventional square, and the square is supported on a tripod formed to represent the conventional legs of a marking or measuring compass.

I claim:

The ornamental design for a candlestick, as shown and described.

In testimony that I claim the foregoing as my own I have hereto affixed my signature in the presence of two witnesses.

HARVEY E. SHUMWAY.

Witnesses:

J. S. DAVIS,
G. R. CARVER.
